UNITED STATES PATENT OFFICE

110,241

DESIGN FOR A SORTING DEVICE

Reuben H. Chambers, Washington, D. C.

Application April 15, 1938, Serial No. 76,548

Term of patent 3½ years

To all whom it may concern:

Be it known that I, Reuben H. Chambers, a citizen of the United States, residing at 1808 Eye Street, N. W., in the city of Washington, District of Columbia, have invented a new, original, and ornamental Design for Sorting Devices, of which the following is a specification, reference being had to the accompanying drawing, forming part thereof.

In the drawing,

Fig. 1 is a front elevation of a sorting device, showing my new design;

Fig. 2 is a side elevation thereof.

I claim:

The ornamental design for a sorting device, as shown.

REUBEN H. CHAMBERS.
